UNITED STATES PATENT OFFICE

136,360

DESIGN FOR AN AIRPLANE

Verne L. Hudson and Harold W. Zipp, Wichita,
Kans., assignors to Boeing Airplane Company,
Wichita, Kans.

Application November 17, 1942, Serial No. 108,808

Term of patent 7 years

To all whom it may concern:

Be it known that we, Verne L. Hudson and Harold W. Zipp, citizens of the United States, residing at Wichita, in the county of Sedgwick and State of Kansas, have invented a new, original, and ornamental Design for an Airplane, of which the following is a specification, reference being had to the accompanying drawings, forming part thereof.

Fig. 1 of the drawings is a top plan view of an airplane embodying the new design;

Fig. 2 is a front elevational view of the air-

plane illustrated in Fig. 1, and shows the landing gear extended;

Fig. 3 is a side elevational view of the same airplane, also showing the landing gear extended; and

Fig. 4 is a bottom perspective view of the same airplane in flight, with landing gear retracted.

We claim:

The ornamental design for an airplane, substantially as shown.
